UNITED STATES PATENT OFFICE.

HERBERT S. PULLMAN, OF MERIDEN, CONNECTICUT, ASSIGNOR OF ONE-HALF TO JESSE STEARNS, OF NEW YORK, N. Y.

GARMENT-FASTENER.

SPECIFICATION forming part of Letters Patent No. 767,957, dated August 16, 1904.

Application filed March 31, 1904. Serial No. 200,912. (No model.)

To all whom it may concern:

Be it known that I, HERBERT S. PULLMAN, a citizen of the United States, and a resident of Meriden, in the county of New Haven and State of Connecticut, have invented a certain new and Improved Garment-Fastener, of which the following is a specification.

My improvement relates more especially to that form of garment-fastening known as a "hook and eye," and the object of my invention is to provide a device of this class the members of which may not be accidentally disengaged each from the other, thus providing a secure fastening means for the garment; and a further object is to provide a device of this class in which the members of the fastener may be readily engaged and disengaged when desired.

One form of fastener embodying my invention and in the use of which these objects may be attained is illustrated in the accompanying drawings, in which—

Figure 1 is a top plan view of a disengaged hook and eye embodying my invention. Fig. 2 is a top plan view of the hook and eye shown as engaged. Fig. 3 is a like view, but showing the parts partly engaged. Fig. 4 is an edge view of the hook and eye.

In the accompanying drawings the numeral 1 denotes my improved eye, and the numeral 2 a hook, embodying my invention. The eye is formed, preferably, of a single piece of metal, as wire, bent to shape. This eye has loops 3, serving as fastening means, and a socket 4 for the reception of the hook. Each of the members of this eye are composed of a double strand of wire, the strands being located a slight distance apart. The outer strand of the socket member is continuous; but the inner strand is separated, as at 5, the adjacent ends, as at the separated portion, forming each end of the wire constituting the entire eye. This socket is preferably of curved form, as shown, and the opening into the socket constitutes a throat 6 of contracted proportions. The formation of the two strands constituting the socket member affords a yielding of one strand, constituting the inner strand of the socket, to a degree sufficient to permit the

entry of the other fastening member when 50 pressed by the hook 2. The hook 2 is provided with loops 7, constituting the usual fastening means, and the bill 8 of the hook is enlarged laterally. In the form shown this bill is preferably of triangular shape and is of a 55 width practically equal to the outside diameter of the socket 4 of the eye, so that it will be impossible to disengage the hook from the eye by passing the bill through the socket 4. In fact, the only way in which the two parts may 60 be disengaged will be by passing the two members while in practically parallel position along each other until the bend in the hook or bill has passed through the throat 6 and the cross-bar 9 of the hook has been located 65 well outside of said throat 6.

From this construction it will be seen that the hook cannot be disengaged from the eye by a tipping movement of the parts one upon the other, but that the parts will be held 70 securely in engagement until the proper relative movement between the parts is given, and this will ordinarily occur only when it is desired to disengage the two members one from the other.

The construction of the eye with two strands of wire provides an extremely cheap form of socket member and one in which the desired resiliency to admit the entrance of the hook is secured.

While I have shown one form of embodiment of my invention, it is obvious that this may be departed from to a considerable extent without departing from the invention, and I do not, therefore, desire to limit myself to the exact form herein shown and described.

My improved eye presents an extremely neat appearance, the strands composing the eye lying practically parallel with each other. 90 The hook engages within the strand, forming the inner member of the socket, so that there is no difficulty in disengaging the parts and no liability of the hook becoming lodged between the two strands. The ends of the wire 95 composing the two strands meeting within the socket member affords a sufficient resiliency of the socket member to permit the ready en-

gagement of the hook, and at the same time no projections are formed upon which threads or the fabric will catch.

What I claim as my invention, and desire to 5 secure by Letters Patent, is—

1. A socket member for a garment-fastener composed of a single piece of wire having the hook-engaging socket formed of two strands, the inner of which includes the meeting ends 10 of a single strand, forming the complete socket member, said inner strand arranged to be normally engaged by and oppose further inward movement of the hook.
2. A garment-fastener including a socket member composed of a single piece of wire 15 including two strands, the socket of which includes in its formation the meeting ends of said two strands, the inner of which is arranged to be normally engaged by and oppose 20 further inward movement of the hook, said socket having a contracted throat for the reception of the hook.
3. A socket member for a garment-fastener composed of a single piece of wire forming 25 two strands lying practically parallel with each other, the hook-engaging socket including the meeting ends of said strands, the inner of which is arranged to be normally engaged by and oppose further inward move- 30 ment of the hook.
4. A socket member for a garment-fastener composed of a single piece of wire formed of

two strands lying practically parallel with each other and including eyes and a hook-engaging socket, the latter including the meeting ends of said strands the inner of which is adapted to be normally engaged by and oppose further inward movement of the hook, and having a contracted throat.

5. A socket member for a garment-fastener 40 composed of a single piece of wire formed of two strands with eyes located outside of and at the side of the socket member, said socket including a contracted throat formed by one of the strands, the meeting ends of which ad- 45 join within the socket.

6. A socket member for a garment-fastener composed of a single piece of wire formed of two strands and including eyes located outside of and in line with the socket, the latter 50 having a contracted throat formed by one of the strands, the meeting ends of which adjoin within the socket.

7. A socket member for a garment-fastener composed of a single piece of wire forming 55 two strands having the same general shape and including eyes located outside of and in line with said socket, one of said strands forming a contracted throat and its meeting ends adjoining within the socket.
